OIL RETURN DEVICE FOR AMMONIA SYSTEMS

Richard H. Swart, Beloit, Wis., assignor to General Refrigeration Corporation, Beloit, Wis., a corporation of Delaware

Application January 17, 1938, Serial No. 185,331

11 Claims. (Cl. 62—115)

The invention relates to refrigeration and has reference more particularly to improved equipment for refrigerating systems using ammonia or other refrigerant liquids lighter than and immiscible in oil for removing the oil from the liquid refrigerant and short circuiting the same directly back into the crank case of the compressor.

It is necessary in the compression expansion types of refrigerating systems to properly lubricate the compressor. However, with proper lubrication of the compressor it is difficult to prevent the oil from travelling up the cylinder walls and passing over into the liquid line along with the refrigerant. Various forms of traps have heretofore been used mostly in the hot gas discharge line between the compressor and condenser. Effective oil separation can not be produced at this point because the oil is partially in the form of a very fine mist or spray which resists separation. As regards ammonia systems the oil is insoluble in the liquid refrigerant and will settle to the bottom when mixed therewith in much the same manner as water will in oil.

Accordingly, the invention contemplates separation of the oil from liquid ammonia by means of a trap located in the liquid line whereby the oil may be drawn off with or without some of the refrigerant. The present apparatus makes it possible to use plenty of oil for lubricating the compressor, notwithstanding that some of the oil may leave the compressor along with the refrigerant since this is separated and short circuited directly back into the crank case of the compressor.

A more specific object of the invention is to provide improved means for ammonia refrigerating systems for separating the oil from the liquid refrigerant and which will be applicable to systems fed with a high side float, low side float, or thermal expansion valve.

Another object is to provide oil removal means which will remove oil from the liquid refrigerant by means of a by-pass circuit of refrigeration that may be automatically controlled by a thermal expansion valve.

With these and various other objects in view the invention may consist of certain novel features of construction and operation as will be more fully described and particularly pointed out in the specification, drawings and claims appended hereto.

In the drawings which illustrate an embodiment of the invention and wherein like reference characters are used to designate like parts—

Figure 1 is a diagrammatic view illustrating the improvements of the invention as applied to an ammonia refrigerating system;

Figure 2 is a fragmentary enlarged view showing the header for the flooded low side evaporating unit used in the refrigerating system of Figure 1;

Figure 3 is a sectional view of the float and valve for the evaporating unit shown in Figure 2;

Figure 4 is a diagrammatic view illustrating a modified form of oil return device showing the same applied to an ammonia refrigerating system; and

Figure 5 is also a diagrammatic view illustrating another modification for removing oil from the liquid refrigerant and returning the same to the compressor.

Referring to the drawings, the refrigerating system shown in Figure 1 includes the compressor indicated by the numeral 10 which is driven by the motor 11, the said compressor and motor being supported by the stand 12. The compressor has connection with the suction line 14 which delivers to said compressor gaseous refrigerant. Said refrigerant upon leaving the compressor is at a high pressure and temperature and the same is thereby passed through the condenser 15 which may be of the air cooled or water cooled type. The lower end of the condenser has connection with the liquid receiver 16 which forms a reservoir for the liquid refrigerant.

The king valve 18 controls the flow of the liquid refrigerant to the oil return device which, in accordance with the invention, includes the cylindrical container or trap 20 and the evaporating coil designated by numeral 21. The liquid line 22 connects with the bottom of the container 20 and at its other end joins with the expansion valve 23. The evaporating coil 21 is supplied with refrigerant by said valve which is expanded during its travel through the coil, being eventually delivered as a gas to the suction line 24 having connection with the main suction line 14 leading to the compressor. The expansion valve 23 is thermostatically controlled by the bulb 25 connecting with said valve through the capillary tube 26.

The liquid line 28 leads from the upper end of the container 20 and connects with the underside of the header 30 of the main evaporator of the refrigerating system. As shown in Figures 2 and 3 the suction line 14 has connection with the top side of said header and also connecting with said header are a plurality of evaporating coils 31.

2
5 One end of each coil joins with the header on the underside thereof, thereby providing an inlet for the liquid refrigerant. The other end of each coil connects with the header in the upper portion thereof in substantial alignment with the suction line 14 so that the returning gas from the several evaporating coils is conducted from the header by said suction line.

10 The evaporating unit above described is known as the flooded, low side type wherein the evaporating coils are flooded with liquid refrigerant, the supply of which to the header is controlled by the float 33 shown in Figure 3. The valve stem 34 secured to the float is pivotally supported by the standard 35, the said stem having connection at its free end with the valve 36. The liquid refrigerant supplied by line 28 is admitted to the header when the valve 36 is lifted from its seat 37. Such lifting of the valve will occur when the float 33 drops below a horizontal plane approximately coinciding with the center of the header 30. Accordingly, when the liquid level in the header is above said horizontal plane the float 33, which is designed to float in liquid ammonia will 25 actuate valve 36 to close the same.

In the flooded or trapped type of evaporating unit it is necessary that the liquid refrigerant delivered to the evaporator be absolutely free of oil in order to insure efficient operation of the system. The invention therefore contemplates interposing an oil trap in the liquid line 28. In ammonia systems the oil is insoluble in the liquid refrigerant and therefore any oil carried along with the liquid refrigerant will settle to the bottom of the container or trap 20. The oil and some liquid refrigerant will be conducted by the line 22 to the thermostatic expansion valve 33. The refrigerant in its travel through the evaporating coil 21 will be expanded. Said coil is a continuous, one pipe gravity return coil and therefore the return line 24 will deliver the gaseous refrigerant and also any oil that may be included therewith to the suction line 14 and thus to the compressor. The liquid line 28 has 45 connection with the upper portion of the container 20 and therefore the liquid refrigerant delivered to said line is free of oil.

An alternative construction applicable to the form of the invention shown in Figure 1 consists 50 in substituting a single expansion valve for the float controlled liquid refrigerant supply means shown. Such expansion valve is constructed to feed liquid refrigerant to the several coils 31, and a unit of this nature is generally referred to as the flooded, header type which also requires that the refrigerant supplied thereto be free of oil if satisfactory and efficient operation is to be secured.

As a result of the oil removing device of the 60 invention the main evaporating unit is supplied with pure liquid refrigerant entirely free of oil and therefore, notwithstanding that said unit is of the flooded or trapped, low side type, high operating efficiency is assured. All the oil and of course some liquid refrigerant is passed through the single evaporating coil 21 which may be described as a by-pass circuit of refrigeration automatically operated by means of a thermal expansion valve for by-passing the oil and returning 65 the same to the compressor. In operation of the refrigerating system constructed as above described the thermal expansion valve 23 may be valved to the receiver 16 or the trap 20 and therefore said expansion valve may be readily replaced without even stopping the refrigeration

70 to the main evaporators. An added advantage inherent in this construction is the fact that an adequate high pressure filter may be put in the liquid line 22 leading from the trap 20 to the said expansion valve, making it possible to clean this oil to a high degree before setting it back to the compressor. The construction also permits the use of large scale traps or dirt accumulators in the main suction line without requiring means for returning any oil from them to the 10 compressor.

In the modification shown in Figure 4 the king valve 18 controlling the flow of liquid refrigerant from the receiver 16 has connection through line 39 to the cylindrical container or trap 40, 15 which, in combination with the evaporating coil 41, comprises the oil return device of this modification. The liquid line 28 leads from the upper portion of the container 40 to the header 30 as described with respect to the refrigerating system 20 of Figure 1. The main evaporating unit shown in Figure 4 is also of the flooded or trapped, low side type having a plurality of evaporating coils 31 connecting with said header which in turn has connection with the suction line 14, whereby 25 the refrigerant gas is returned to the compressor.

The liquid line 42 has connection with the bottom of the container 40 and leads to the thermal expansion valve 43, which delivers the liquid refrigerant in controlled amounts to the evaporating coil 41. Said coil in this modification is in the form of a spiral and is located within the said container 40. The suction line 44 from said evaporating coil joins with the main suction line 14 and therefore the gaseous refrigerant and any 35 oil that may travel along therewith will be returned to the compressor.

In this modification the refrigeration produced by the evaporating coil 41 is used to pre-cool the liquid refrigerant which is fed as pure liquid refrigerant to the flooded low side evaporating unit. Also the coil 41 forms a by-pass circuit whereby the oil may be by-passed to the compressor.

In the modification of Figure 5 the refrigerating system is substantially the same as that described with respect to Figures 1 and 4. However, the container or oil return trap in this modification takes the form of a liquid receiver 50. The liquid refrigerant having oil mixed therewith is delivered to the receiver 50 by the pipe 51 having 50 connection through the king valve 18 with the main liquid receiver 16 of the compressor unit. In the trap or receiver 50 the oil suspended in the liquid will gradually settle out and collect on the bottom. The liquid line 28 to the evaporating unit extends into said trap 50 and depends below the liquid level therein but does not come in contact with the oil. In other words, the end of said liquid line is located above the oil level in the trap or receiver 50. Thus, in operation the 60 oil is effectively removed from the liquid refrigerant and the same in substantially pure form is supplied to the line 28.

In accordance with the invention the oil level within the trap 50 is maintained approximately 65 constant by the float 52 which is designed to sink in liquid ammonia but float in oil. The end of the valve stem 53 is pivotally supported by the support 54 and intermediate thereof said stem carries the valve 55. Movement of the valve 55 70 with respect to its seat will control the oil delivered to the oil return line 56 connecting with the suction line 14. In this modification the oil is effectively separated from the liquid refrigerant but instead of making use of a by-pass circuit 75

of refrigeration there is substituted for said circuit an oil return line and float control means whereby oil in its pure form and without having mixed therewith any of the liquid refrigerant is sent directly back to the compressor.

What is claimed is:

2. An oil separation and return device for refrigeration systems using ammonia or other refrigerant liquids lighter than and immiscible in oil and including a compressor and a main evaporating unit, in combination, a trap located in the liquid line to the main evaporating unit for separating the oil from the liquid refrigerant, and an auxiliary evaporating unit having connection with said trap, said connection being constructed and arranged to feed the separated oil along with any liquid refrigerant in admixture therewith to said auxiliary evaporating unit, whereby the oil is returned to said compressor along with the expanded refrigerant from the auxiliary unit, said auxiliary unit comprising a continuous coil of the non-trapped type.

and a main evaporating unit of the flooded or trapped low side type, in combination, a container located in the liquid line to said evaporating unit forming a trap for separating the oil from the liquid ammonia, said liquid line having connection with the upper portion of said container and thereby supplying to said evaporating unit pure liquid refrigerant, an auxiliary evaporating unit having connection with said trap whereby the oil separated by said trap is delivered to said auxiliary evaporating unit along with any liquid refrigerant in admixture therewith, said auxiliary unit comprising a continuous gravity return coil having connection at its other end with the compressor and which thereby returns oil to the compressor along with the expanded

3. An oil separation and return device for refrigeration systems having a compressor and a main evaporating unit of the flooded or trapped low side type, in combination, a trap located in the liquid line to said evaporating unit for separating the oil from the liquid refrigerant, an auxiliary evaporating unit having connection with said trap, said auxiliary unit comprising a continuous gravity return coil having an expansion valve, whereby the separated oil from the trap along with any liquid refrigerant in admixture therewith is fed to said auxiliary evaporating unit, said auxiliary unit connecting at its other end with the compressor and which thereby returns the oil to the compressor along with the expanded refrigerant from said auxiliary unit.

4. An oil separation and return device for refrigeration systems of the compression-expansion type, in combination, a trap located in the liquid line for separating the oil from the liquid refrigerant, and an auxiliary evaporating unit having connection with the bottom of said trap whereby the oil in said trap along with any liquid refrigerant in admixture therewith is delivered to said auxiliary unit, a portion of said unit having location within the trap whereby the liquid refrigerant in the trap is maintained at a low temperature.

5. An oil separation and return device for refrigeration systems having a compressor and a main evaporating unit of the flooded or trapped low side type, in combination, a trap located in the liquid line to said evaporating unit for separating the oil from the liquid refrigerant, an auxiliary evaporating unit having connection with said trap, said auxiliary unit comprising a continuous gravity return coil having an expansion valve, whereby the separated oil from the trap along with any liquid refrigerant in admixture therewith is fed to said auxiliary evaporating unit, said auxiliary unit connecting at its other end with the compressor and which thereby returns the oil to the compressor along with the expanded refrigerant from said auxiliary unit.

6. An oil separation and return device for refrigeration systems of the compression-expansion type, in combination, a trap located in the liquid line for separating the oil from the liquid refrigerant, and an auxiliary evaporating unit having connection with the bottom of said trap whereby the oil in said trap along with any liquid refrigerant in admixture therewith is delivered to said auxiliary unit, a portion of said unit having location within the trap whereby the liquid refrigerant in the trap is maintained at a low temperature.

7. An oil separating and return device for refrigeration systems having a compressor and a main evaporating unit of the flooded or trapped low side type, in combination, a trap located in the liquid line to said evaporating unit for separating the oil from the liquid refrigerant, an auxiliary evaporating unit having connection with said trap, said auxiliary unit comprising a continuous gravity return coil having an expansion valve, whereby the separated oil from the trap along with any liquid refrigerant in admixture therewith is fed to said auxiliary evaporating unit, said auxiliary unit connecting at its other end with the compressor and which thereby returns the oil to the compressor along with the expanded refrigerant from said auxiliary unit.

8. An oil separating and return device for refrigeration systems of the compression-expansion type, in combination, a trap located in the liquid line for separating the oil from the liquid refrigerant, and an auxiliary evaporating unit having connection with the bottom of said trap whereby the oil in said trap along with any liquid refrigerant in admixture therewith is delivered to said auxiliary unit, a portion of said unit having location within the trap whereby the liquid refrigerant in the trap is maintained at a low temperature.

9. An oil separating and return device for refrigeration systems having a compressor and a main evaporating unit of the flooded or trapped low side type, in combination, a trap located in the liquid line to said evaporating unit for separating the oil from the liquid refrigerant, an auxiliary evaporating unit having connection with said trap, said auxiliary unit comprising a continuous gravity return coil having an expansion valve, whereby the separated oil from the trap along with any liquid refrigerant in admixture therewith is fed to said auxiliary evaporating unit, said auxiliary unit connecting at its other end with the compressor and which thereby returns the oil to the compressor along with the expanded refrigerant from said auxiliary unit.

10. An oil separating and return device for refrigeration systems of the compression-expansion type, in combination, a trap located in the liquid line for separating the oil from the liquid refrigerant, and an auxiliary evaporating unit having connection with the bottom of said trap whereby the oil in said trap along with any liquid refrigerant in admixture therewith is delivered to said auxiliary unit, a portion of said unit having location within the trap whereby the liquid refrigerant in the trap is maintained at a low temperature.

expanded refrigerant from said auxiliary unit connecting at its other end with the compressor so that the oil separated by the trap is returned to the compressor of the system along with the expanded refrigerant from said auxiliary unit.

8. An oil separation and return device for refrigeration systems having a compressor and a main evaporating unit of the flooded or trapped low side type, in combination, a container located in the liquid line to said evaporating unit forming a trap for separating the oil from the liquid ammonia, said liquid line having connection with the upper portion of said container and thereby supplying to said evaporating unit pure liquid refrigerant, and an auxiliary evaporating unit having connection with the bottom of said container whereby the oil separated by the trap is delivered to said auxiliary evaporating unit along with any liquid refrigerant in admixture therewith, said auxiliary unit comprising a continuous gravity return coil having an expansion valve and connecting at its other end with the compressor to thereby return the oil to the compressor along with the expanded refrigerant from said auxiliary unit.

5. An oil separation and return device for ammonia refrigeration systems having a compressor and a main evaporating unit of the flooded or auxiliary unit.

oil separated by the trap is returned to the compressor along with the expanded refrigerant from said auxiliary unit.

9. An oil separation return device for refrigeration systems having a compressor and a main evaporating unit of the flooded or trapped low side type, in combination, a container located in the liquid line to said evaporating unit forming a trap for separating the oil from the liquid refrigerant, an auxiliary evaporating unit having connection with the bottom of said container whereby the oil in the trap along with any liquid refrigerant in admixture therewith is fed to said auxiliary evaporating unit, said auxiliary unit comprising a continuous gravity return coil provided with an expansion valve, a portion of said auxiliary unit having location within the container and said unit connecting at its other end with the compressor whereby the liquid refrigerant within the container is maintained at a low temperature and the oil is returned to the compressor along with the expanded refrigerant from said auxiliary unit.
10. The method of removing oil from liquid refrigerants lighter than and immiscible in oil, which consists in conducting the mixture of liquid refrigerant and oil to a quiescent chamber and separating the oil therefrom by gravity, con-

ducting the pure liquid refrigerant to the evaporator of the refrigerating system, supplying said oil and any liquid refrigerant admixed therewith to an auxiliary evaporating coil, expanding the refrigerant mixed with said oil in said auxiliary evaporating coil, and delivering said oil along with the expanded refrigerant to the suction line of the system, whereby the oil is eventually returned to the compressor of the system.

11. The method of operating a refrigerating system using a liquid refrigerant lighter than and immiscible in oil, which consists in conducting a mixture of liquid refrigerant and oil to a quiescent chamber for separating the oil from said liquid refrigerant by gravity, conducting the pure liquid refrigerant to the evaporator of the system, supplying said oil along with any liquid refrigerant in admixture therewith to an auxiliary evaporating coil, expanding the liquid refrigerant mixed with the oil in said auxiliary evaporating coil, and delivering said oil along with the expanding refrigerant to the suction line of the system, whereby the oil is eventually returned to the compressor of the system.

RICHARD H. SWART. 25
